Arthur C. Webb.

UNITED STATES PATENT OFFICE.

SAMUEL SHORT, OF BROOKLYN, NEW YORK.

EGG OR BATTER BEATER.

SPECIFICATION forming part of Letters Patent No. 273,173, dated February 27, 1883.

Application filed December 4, 1882. (No model.)

To all whom it may concern:

Be it known that I, SAMUEL SHORT, a citizen of the United States, residing at Brooklyn, in the county of Kings and State of New York, have invented certain new and useful 5 Improvements in Egg or Batter Beaters, of which the following is a full, clear, and exact description.

The object of the invention is the production of a beater capable of beating eggs or batter with less labor and more rapidly than could heretofore be done by hand or by other beaters now in use.

My invention consists of a stationary beater provided with cross-bars or arms arranged at suitable distances apart, cast in one piece with the shaft, and connected to a handle, to which is geared a crown-wheel adapted to engage with a peculiarly-shaped pinion, which answers the double purpose of imparting a revolving motion to a frame provided with cross-bars or arms cast in one piece with the frame, and of supporting the upper end of said frame, and also in the details of construction, all as hereinafter more fully pointed out.

In the accompanying drawing a front elevation, partly in perspective, of an egg or batter beater is shown.

The letter A designates a beater made of metal, provided with cross-bars or arms a, cast in one piece; and B designates a frame, also of metal, and provided with cross-bars or arms b, cast in one piece, the cross-bars or arms b, as the frame B moves, being adapted to revolve in the spaces between the bars a, the bars a remaining stationary in the spaces between the bars b. The lower end of the stem S of the beater A is contracted to fit in an open slot, s, in the lower end of the frame B, and the upper end of the stem S screws into a handle, H, also cast in one piece. Near the upper end of the stem S, a shoulder, X, is formed, and between this shoulder X and the lower end of the handle H a pinion, P, is set, and rotates loosely on the stem S. The upper end of the frame B is provided with an open slot, in which the stem S rests, and the pinion P is provided with sleeves e, which grasp both sides of the upper end of the frame 50 B and hold it firmly in position.

A crown-wheel, C, having a crank, h, by which motion may be imparted to it, is geared to the handle H. This crown-wheel C engages with the pinion P, and when put in motion revolves the frame B, the beater A remaining stationary.

It will be seen that the slot at the upper end of the frame is on one side and the slot at the lower end on the other, thus bringing the central portions of the cross-bars b against the stem S, between the cross-bars a, and preventing any displacement of the beater or frame. The central portions of the cross-bars are also slightly concave where they bear against the stem S, to facilitate the revolving motion of the bars when the frame is operated, and to lessen the strain on the beater and frame.

In most egg-beaters heretofore in use a central vacuum is created, driving the material to be beaten away from the beater, whereas by my invention this is obviated, the fans creating a current and drawing the material to the beater.

My beater is also especially adapted for beating batter, as it is much stronger than beaters heretofore in use.

By my invention I do away with the necessity of solder-joints, the beater and its cross-bars, the frame and its cross-bars, and the handle, being each cast in one piece, thereby requiring less labor in manufacture and considerably lessening the cost of the complete article, and at the same time increasing its strength and efficiency.

What I claim as my invention, and desire to secure by Letters Patent, is—

1. A stationary beater having a series of cross-bars or arms extending radially from a stem one end of which is screwed into a handle carrying a crown-wheel adapted to engage with a pinion revolving loosely on the stem of the beater, said pinion having portions adapted to grasp both sides of the upper end of a movable frame, whereby said frame is held in place, and may be rotated under an impulse from the crown-wheel, substantially as herein shown and described, for the purposes set forth.

2. A movable frame the ends of which are slotted on opposite sides to receive the stem 100

of a stationary beater having a series of cross-bars or arms, said frame being provided with a series of cross-bars or arms having concave central portions bearing against the stem of the beater, between its cross-bars or arms, and adapted to be held in place and rotated by means of a pinion, to which motion is imparted by a crown-wheel, substantially as

herein shown and described, for the purposes set forth.

In testimony whereof I have hereunto set my hand.

SAMUEL SHORT.
